BOILER SUPERHEATER SUPPORT

Howard J. Kerr, Westfield, N. J., and William A. Jones, Westerleigh, N. Y., assignors to The Babcock & Wilcox Company, Bayonne, N. J., a corporation of New Jersey

Application March 4, 1930, Serial No. 433,021

10 Claims. (Cl. 122—478)

This invention relates to a boiler of the Babcock & Wilcox type having a superheater supported upon the bank of inclined tubes with provision to permit the superheater tubes that 5 are connected with the superheater outlet header to move laterally when this header expands and contracts.

The invention will be understood from the description in connection with the accompanying drawings in which Fig. 1 is a vertical section through an illustrative embodiment of the invention; Fig. 2 is a similar section through a modification; Fig. 3 is a section along the line 3—3 of Fig. 4; Fig. 4 is a section along the line 4—4 of Fig. 3; Fig. 5 is a section along the line 5—5 of Fig. 6; Fig. 6 is a section along the line 6—6 of Fig. 5; Fig. 7 is a section along the line 7—7 of Fig. 8; and Fig. 8 is a section along the line 8—8 of Fig. 7.

20 In the drawings, reference character 1 indicates the steam and water drum of the boiler, the water space of which is connected by means of the nipples 2 to the upper ends of the downtake headers 3. A bank of inclined tubes 4 connects the headers 25 3 to the uptake headers 5, and the upper ends of the uptake headers 5 are connected by means of the circulating tubes 6 to the steam space of the steam and water drum 1. The uptake headers 5 are supported by means of supporting rods 7 that 30 may be connected to supports 7' outside of the boiler setting.

A pipe 8 leads from the steam space of the steam and water drum 1 to the superheater inlet header 9 that is located above the upper ends of the inclined tubes 4 and protected from hot gases by baffles. Return bend tubes 10 connect the inlet header 9 to the outlet header 11 of the superheater. The tubes 10 are each provided with several return bends and the return bends 40 near the headers 9 and 11 may be supported upon a support or baffle 12 that rests upon the tubes 9, with the projections 13 on the return bends extending through holes in the support or baffle 12. Tile 12' are located on the gas side of the support 45 or baffle 12. A support 10' may be provided near the other end of the superheater tubes 10, this support also resting upon the tubes 4.

In the modification shown in Fig. 2, the superheater headers 9 and 11 are located outside of the boiler setting. Supports 14 and 15 are provided for the superheater tubes 10, these supports resting upon the tubes 4. A baffle 16 that may be lined on the gas side with tile 16' supports the return bends of the superheater tubes 10 near 55 the headers 9 and 11.

Due to the fact that the outlet header of the superheater reaches a higher temperature than the inlet header, this header expands more than the inlet header, so that if the upper row of tubes 10 were to be immovably supported, the portions 60 of these tubes between the support and the superheater header 11 would be subjected to considerable flexure with the danger of loosening these tubes in the header. By the present invention, provision is made for permitting these portions 65 of the tubes 10 to move with the header 11, thus distributing the flexure over long distances along the tubes. One of the ways of providing this feature is indicated in Figs. 3 and 4 in which a portion 17 of the support that is located near the 70 superheater headers through which the uppermost portions of the rows of tubes 10 pass is made in sections and is movable horizontally with respect to the remainder of the support or baffle 12. The portion 17 is made of sections or strips of 75 plate metal that are connected by means of bolts 17' to the remainder of the support both along the upper and lower edges of the sections 17 that pass through holes 18 in the support 12 that are elongated horizontally so as to permit movement 80 of the sections or portions 17 horizontally with respect to the remainder of the support. The holes 19 in the sections 17 through which the tubes 10 pass may be made slightly larger than the tubes 10.

Another way of providing for the lateral movement of the upper portions of the tubes 10 is illustrated in Figs. 5 and 6, that is suitable when the superheater headers are located outside of the boiler setting. In these figures reference 90 character 20 indicates the portions or sections of the support through which the upper portions of the tubes 10 pass. The sections 20 are provided with hook shaped flanges 21 at the upper and lower edges with other correspondingly shaped flanges 22 on the remainder of the support so that the sections 20 will be kept in place and can move with the movement of the tubes 10 as they are moved by the expansion and contraction of the outlet header of the superheater. 95

In the modification shown in Figs. 7 and 8, the support for the end of the superheater near the headers is by means of the baffle 23 that is supported upon an upper bank of inclined tubes 4. The lower edge of the support or baffle 23 is provided with hooked flange 24 to support the sections 25 through which the upper portions of the tubes 10 pass. The sections 25 are provided with hooked flanges 26 and 27 so that these sections will be supported by the support 23 and will in 100 105 110

turn support the remainder 28 of the support that is provided with the hooked flange 29 at its upper edge.

We claim:

5. 1. In a superheater support, means comprising slidable plates for supporting a row of superheater tubes so that they may move laterally with respect to each other.
10. 2. In a superheater, an outlet header, a row of superheater tubes connected to said header, a support for said tubes near said header permitting said tubes to move apart as said header expands, and a support for other tubes of said superheater supported by said first named support.
15. 3. In a superheater comprising return bend tubes, a support at said return bends, a portion of said support being slidable with respect to the remainder thereof.
20. 4. In a superheater comprising return bend tubes, a support at said return bends, a portion of said support being slidable with respect to the remainder thereof and sustaining said remainder.
25. 5. In a superheater comprising return bend tubes, a support at said return bends, a portion of said support being slidable with respect to the remainder thereof, and tubes of said superheater extending through said slidable portion of said support.
30. 6. In a steam superheater, a gas pass wall formed with two spaced rows of tube openings, a superheater inlet header, a row of superheater inlet tubes extending from the header through the openings of one of said rows into the gas pass, a superheater outlet header, a row of superheater outlet tubes extending from the outlet header through the other row of openings and into the gas pass, and sections movable relatively to each other longitudinally of the outlet header and constituting that portion of the wall through which the outlet tubes extend and supporting the tubes, there being a plurality of outlet tube openings in some of said sections.

7. In a furnace, a baffle support, a plurality of horizontally aligned and relatively movable separate baffle sections slidably hung from the support, a fixed lower section suspended from said sections, and relatively movable groups of superheater tubes passing through the relatively movable sections.

8. In a fluid heater having connected tubes extending across a gas pass, a header, a support for the tubes including a part interfitting with certain of the tubes only so as to be movable in unison therewith and slidable with respect to the remainder of the support and longitudinally of the header, said part having its interfitting and associated tubes extending through openings therein.

9. In combination, superheater tubes conducting steam across a gas pass, a baffle having the outlet portions of the superheater tubes extending through and beyond one part and the inlet portions of the tubes extending through and beyond another part, a superheater outlet header spaced from the baffle and having the outlet portions connected thereto, and means for connecting the inlet portions of the tubes to a source of steam, the first part of the baffle constituting separate sections relatively movable longitudinally of the outlet header and supporting the outlet portions of the tubes so that some of the tubes may move longitudinally of the header relative to others.

10. In a suspended baffle construction, a plurality of successive sections each having formations so that each section is hooked to the one above it, and fluid heat exchange tubes receiving heat from the furnace, one of said sections consisting of a plurality of separate parts movable relative to each other and to the other sections with each part so related to the tubes that it is moved by a group of those tubes.

HOWARD J. KERR.
